[57] CLAIM

The ornamental design for a tree sculpture or the like,
substantially as shown and described.

DESCRIPTION

FIG. 1 is a perspective view of a tree sculpture or the
like showing my new design;

FIG. 2 is a front elevational view thereof;

FIG. 3 is a top plan view thereof;

FIG. 4 is a rear elevational view thereof;

FIG. 5 is a perspective view of a tree sculpture or the
like showing a modified form of my new design;

FIG. 6 is a front elevational view thereof;

FIG. 7 is a top plan view thereof; and

FIG. 8 is a rear elevational view thereof.
